STRAP STRETCHING DEVICE

William C. Childress, Oak Park, Ill., assignor to
 Acme Steel Company, Chicago, Ill., a corporation
 of Illinois

Original application February 10, 1932, Serial No.
 592,050. Divided and this application January
 30, 1934, Serial No. 708,986. Renewed February
 25, 1937.

11 Claims. (Cl. 140—93)

This invention relates to improvements in strap stretching and sealing devices and the present application is a division of my co-pending application Serial No. 592,050, filed February 10, 1932, 5 in which there is disclosed a strap stretching and sealing device adapted to draw a flexible metal strap taut around a box or package, cut off the strap from the source of supply and then form an interlocking joint between the overlapping strap ends by cutting and shearing or otherwise deforming these portions of the strap. The present invention relates particularly to the means which are embodied in said device for drawing the strap taut around the box or package preliminary 10 to the cutting of the strap and the formation of the joint and the principal object of the present invention is to provide improved mechanism for performing this operation of stretching or drawing taut a flexible strap or binder. A further object of the invention is to provide an improved strap stretching device comprising a base having mounted thereon a pair of gripping devices adapted to grip opposite end portions of the strap in combination with a slidably 15 mounted bar carrying one of the gripping devices and means for effecting relative movement of the bar and the base for drawing the strap taut. A further object of the invention is to provide a strap stretching device comprising means for engaging opposite end portions of a strap and effecting relative movement of these portions for drawing the strap taut in combination with means for automatically terminating the tightening operation when a predetermined tension is obtained 20 in the strap. Still another object of the invention is to provide a strap stretching device comprising a base having mounted thereon a pair of relatively movable gripping devices adapted to engage opposite end portions of the strap in combination with mechanism comprising a lever movable transversely to the direction in which the strap extends for effecting movement of said gripping devices. Still another object of the invention is to provide a strap stretching device 25 comprising a yielding connection which is adapted to function after a predetermined degree of tension has been brought about in the strap. Other objects relate to various features of construction and arrangement which will appear more fully hereinafter.

The nature of the invention will be understood from the following specification taken with the accompanying drawings in which one embodiment is illustrated.

55 In the drawings,

Figure 1 shows a side elevation of a box or package with the improved strap stretching and sealing device of the present invention applied thereto for the purpose of drawing a flexible metal strap taut around the package;

Fig. 2 shows a top plan view of the overlapping ends of a metal strap having formed therein the improved interlocking joint which is formed by the operation of the device of the present invention;

Fig. 3 shows a side elevation of the joint illustrated in Fig. 2;

Fig. 4 shows a bottom plan view of the joint illustrated in Fig. 2;

Fig. 5 shows an enlarged transverse section 15 taken on the line 5—5 of Fig. 2;

Fig. 6 shows an enlarged transverse section taken on the line 6—6 of Fig. 2;

Fig. 7 shows an enlarged top plan view of the strap stretching and sealing device of the present invention with parts thereof broken away;

Fig. 8 is a detail sectional view taken on the line 8—8 of Fig. 7;

Fig. 9 shows an enlarged front elevation of the strap stretching and sealing device illustrated in Figs. 1 and 7;

Fig. 10 is a detail vertical section taken on the line 10—10 of Fig. 7;

Fig. 11 is a detail vertical section taken on the line 11—11 of Fig. 9;

Fig. 12 is a detail vertical section taken on the line 12—12 of Fig. 9;

Fig. 13 is a detail section taken on the line 13—13 of Fig. 15;

Fig. 14 is an enlarged vertical section taken on the line 14—14 of Fig. 7, showing the position of the cutting blade or die and of the strap crimping jaws preliminary to their engagement with the straps;

Fig. 15 is a partial vertical section similar to that of Fig. 14, showing the relative positions of the parts after the strap has been cut off from the source of supply by the cutting die and after the crimping jaws have been brought into engagement with the straps;

Fig. 16 is an enlarged vertical sectional view showing the positions of the jaws after they have been brought into final engagement with the overlapping strap ends;

Fig. 17 is an enlarged detail horizontal section 50 taken on the line 17—17 of Fig. 16;

Fig. 18 is an enlarged vertical section taken on the line 18—18 of Fig. 17; and

Fig. 19 is a perspective view of one of the intermediate plates of the crimping jaws.

It is common practice to employ flat flexible steel straps or other binders for reenforcing boxes or packages and also for binding together groups of packages to form load units and the present invention is directed to improved means for drawing taut the strap or binder after it has been passed around the package or group of packages, although it is illustrated in the accompanying drawings in association with the means for cutting off the strap from the source of supply and the means for subsequently crimping and also, preferably, shearing the overlapping strap ends to form an interlocking joint, which features are described and claimed in the co-pending application above referred to. As illustrated in Fig. 1, the strap stretching and sealing device 10 is shown applied to the upper surface of a box or crate 11 and the walls of this box are reenforced by two flat flexible steel straps or binders 12 which are passed around the box. The strap stretching and sealing device 10 is shown in position to engage one of these straps.

The device 10 comprises a base plate 15 which is adapted to rest upon the surface of the box or package and which carries the operating part by which the strap is first stretched, then cut off from the source of supply and finally crimped or otherwise deformed to form an interlocking joint between the ends of the strap. The base plate 15 is provided with a forwardly extending flange 16, spaced slightly above the surface of the box, which is adapted to receive on its upper side the free end 12^a of the strap 12. Adjacent to the flange 16, the base plate carries an upwardly extending block or lug 17 which serves as a support for a gripping dog or detent 18 having a lower serrated or roughened part 18^a which is adapted to coat with the upper side of the strap 12^a to hold the strap firmly in engagement with the flange 16. The gripping dog 18 is rotatably mounted upon a pin or shaft 20 which is fixed in the block 17 by means of a set screw 21. The pin or shaft 20 is provided with a relatively fixed handle 22 which serves as a handle for the detent 18 so that the latter may be moved out of engagement with the upper side of the strap against the compression of a coil spring 23 which is mounted in a recess in the detent and which engages at its upper end a plug 24 mounted in an aperture in the upper flange 17^a of the lug or block 17. This spring thus normally serves to maintain the dependent engagement with the strap and the serrated portion 18^a of the detent is displaced laterally from the pivotal axis of the detent, as shown in Fig. 9, so that a pull upon the strap 12 toward the left as viewed in that figure tends to increase the grip of the gripping dog and flange upon the strap, while a movement of the strap in the other direction tends to effect an automatic release of the strap from the gripping dog. After having the free end 12^a of the strap passed into gripping engagement with the dog 18, the strap is passed around the box or package 11 and the supply portion 12^b of the strap is then carried over the free end 12^a and passed into engagement with a slot 18^b which is formed in the side of the gripping dog 18 as shown particularly in Figs. 9 and 11. For the purpose of maintaining the supply end of the strap in engagement with this slot, the recess in which the spring 23 is mounted is provided at its lower end with a movable ball 25 adapted to project through a tapered aperture in the lower end of the recess so that it is held by the spring 23 in engagement with the lower

wall of the slot 18^b to hold the strap in the slot while permitting the ready insertion or withdrawal of the strap when desired.

For the purpose of stretching the strap 12 around the package, the supply portion 12^b thereof is engaged by another gripping dog 26 which is carried by a block 27 mounted upon the outer end of a slidably mounted bar 28 carried by a plate 15. This bar is adapted to move parallel to the strap which is held by the gripping dog 26 against a flange 27^a which projects forwardly from the block 27. The block 27 is secured to the bar 28 by a stud 29 and it carries a fixed pin or axle 30 upon which the gripping dog 26 is pivotally mounted. The upper edge of the gripping dog is curved to coat with the curved flange 27^b of the block. This flange is concentric with the pin 30 so that the gripping dog is supported independently of the pin. The other end of the gripping dog is provided with a serrated surface 26^a which coats with the upper side of the strap 12 and forces it against the flange 27^a under the influence of a coil spring 31 which engages a socket in the gripping dog and coats with a flange 27^c carried by the block 27. The gripping dog 26 is inclined toward the left as viewed in Fig. 9 so that a pull upon the strap 12^b toward the right will tend to increase the grip of the dog upon the strap while movement of the strap in the other direction will tend to effect an automatic release of the strap from the gripping dog.

With the block 27 and the gripping dog 26 mounted as above described it will be apparent that movement of these members with the bar 28 toward the left, as view in Fig. 9, will draw the strap 12 taut around the box or package 11. The base plate 15 is provided on its upper side with a groove 32, of rectangular cross section, in which the bar 28 is adapted to slide and the base plate is also provided with a recess 33 which is adapted to be engaged by the underside of the block 27, as shown in Fig. 12, during the sliding movement of the bar 28. The bar is maintained in the groove 32 by means of the retaining members 34 which are secured to the base plate by screws 35, as shown in Fig. 7. The sliding movement of the bar 28 is effected by certain operating mechanism comprising a link 37 which extends between two ears 38 carried by one of the members 34, as shown in Fig. 10, and is secured thereto by means of a pivot pin or rivet 39. This link 37 has its other end pivotally connected at 40 with a shifting link 41 which has its forward end inserted between the bar 28 and the reversely bent portion 28^a thereof, as shown in Fig. 10, being pivotally connected thereto by means of the pin 42. The pin 40 carried by the link 37 thus provides a movable fulcrum about which the lever 41 is adapted to pivot in effecting a sliding movement of the bar 28 and this pivotal movement of the lever 41 is effected through the connections which are shown particularly in Figs. 14 and 15. The rear end of the lever 41 carries an upwardly extending pin 43 provided with a spherical head 43^a. This pin is adapted to be inserted through a key-hole slot 44 formed in the wall of a hollow link 45 and the head 43^a is engaged within the hollow link by a coil spring 46, the compression of which may be adjusted by a plug 47 which threadedly engages the end of the link to coat with the end of the spring. The other end of the hollow link 45 is provided with another key-hole slot 48 to receive the head 49^a and the neck of a pin 49 which is secured to

the short arm 50^a of the strap stretching lever 50, the long arm of which extends upwardly as shown in Fig. 9 with a handle 50^b at the upper end thereof for engagement by the hand of the operator. The lever 50 is fixed upon a shaft 51 which is journaled in bushings 52 secured by set screws 52^a within the spaced bearing members 53 and 54 mounted on or formed integrally with the base plate 15, as shown in Fig. 7. When the lever 50 is moved rearwardly, or toward the left as view in Fig. 14, the hollow link 45 is carried forwardly and this causes the spring 46 to move the pin 43 and thus actuate the lever 41 in a forward direction, causing the latter lever to rock about the pin 40 so that it moves bodily from the position shown by full lines in Fig. 7 to the position shown by dotted lines in that figure. This results in shifting the bar 28 toward the left as viewed in Figs. 7 and 9 so that the strap 12 is thereby drawn taut. When a predetermined degree of tautness is obtained in the strap 12, the continued movement of the lever 50 will merely serve to compress the spring 46 within the hollow link 45. During this movement of the operating lever 41, the rear end of that lever is maintained in position adjacent to the base 15 by a plate 55 which is secured by screws 56 to a ledge 57 formed on the base 15, with a part of the plate overlying a portion of the lever 41, as shown particularly in Figs. 7 and 8. An important advantage of this construction is that the operation of the lever 50 produces a rapid relative movement of the blocks 17 and 27 during the early part of the stretching operation when the strap is comparatively slack, while the rapidity of motion decreases and the force exerted upon the strap increases as the final stages of the stretching operation are approached. This permits the tool to be used in stretching a strap in a single operation as compared with the use of several tools or several operations, which has been the practice heretofore.

After the strap has been drawn taut in the manner described above, the end portion 12^b thereof is cut off from the source of supply and the overlapping ends of the strap are then deformed to produce an interlocking joint through the operation of certain mechanism carried by a movable head 59 comprising a pair of flat plates 60, spaced apart in vertical planes, and having their rear ends pivotally mounted upon the shaft 51 as shown in Fig. 7. One plate 60 is maintained in frictional engagement with the side of the bearing hub 53 by means of a coil spring 61 which is mounted on the shaft 51 with one end bearing against the last mentioned plate 60 and with the other end bearing against a collar 62 which is secured against endwise movement on the shaft 51 by means of a transverse pin 63. The other plate 60 is maintained against the bearing hub 54 by means of a plate 64 which is secured to the base plate 15 by means of a screw 65. These plates 60 have mounted between the enlarged forward ends thereof a pair of crimping jaws 66 which are mounted upon a common pivot 67 extending between the plates and which have their arms 66^a extending upwardly with their upper extremities pivotally connected by pins 68 with the upwardly and inwardly inclined links 69, as shown particularly in Fig. 16. The other extremities of these links 69 are connected by pins 70 with spaced points on the lower portion 71^a of an operating lever 71 which is pivotally mounted upon a pin 72 extending between the plates 60. This lever 71 extends upwardly,

when the head 59 is in its normal upper position, as shown in Figs. 9 and 14 and, when the operator wishes to move the head 59 downwardly that movement is first effected by thrusting on the lever 71, while maintaining it in its upright position and then, the lever 71 may be turned about the pivot 72 for the purpose of actuating the links 69 and thereby moving the jaws 66 toward each other to effect the crimping and shearing of the strap ends as hereinafter more fully described. The extent to which this pivotal movement of the lever 71 may be carried is limited by means of a stop member 73 which threadedly engages the lever 71, being held in adjusted position by means of a lock nut 74. The extremity of this adjusting member is adapted to bear against one of the links 69 when the lever 71 is in its lowermost position, as shown in Fig. 16, thus preventing further movement of the jaws 66 toward each other. By adjusting the position of the stop member 73, the minimum separation of the jaws may be varied as desired. The initial downward movement of the head 59 is utilized to effect the cutting off of the strap from the source of supply. The cutting of the strap is effected by a cutting lever 75 which is pivotally mounted on a pin 76 secured in one of the retaining members 34 previously referred to. As shown particularly in Figs. 13 and 14, this lever is provided on one side with a recess 75^a in which is removably mounted the cutting blade or die 77, the die being secured to the lever by means of a screw 78. The die is adapted to extend downwardly past the vertical face of a stationary die 79 which is carried by the adjacent member 34 and which extends forwardly therefrom to underlie the upper portion 12^b of the strap and to extend over the extremity 12^a thereof. The lever 75 has an upwardly extending arm 75^b which is pivoted at 80 to a link 81 pivotally mounted at 82 on the adjacent plate 60 of the head. It will be apparent that when the head 59 moves downwardly, the link 81 will serve to actuate the cutting lever 75 so that the movable cutting die 77 will be moved downwardly to engage the supply portion 12^b of the strap and cut it off by coaction with the stationary die 79, as shown in Fig. 13.

It is desirable to maintain the manually operated lever 71 in its upright position and to prevent relative movement of the jaws 66 toward each other until after the strap has been severed from the source of supply and the jaws have been brought into a position wherein they may embrace the overlapping strap ends. To obtain this result, the plate 64 heretofore described has an arm 64^a extending upwardly and forwardly, as shown in Fig. 14, with a curved surface 64^b adapted to coact with the end of one of the links 69 along the surface which is concentric with the axis of movement of the head 59. As a result of this arrangement, when the operator pushes downwardly on the lever 71 with this lever extending in an upward inclined position, as shown in Fig. 14, the initial downward movement of the head 59 takes place without any relative movement of the jaws 66 due to the coaction of the link 69 with the curved face 64^b of the stationary plate. During this period of movement of the head 59 the cutting lever 75 is actuated to cut off the strap and finally when a point is reached where the jaws 66 are in a position to embrace the overlapping strap ends, as shown in Fig. 15, the end of the link 69 will have passed beyond the curved face 64^b of the

stationary plate so that the links may then separate from each other toward the position shown in Fig. 16. The lever 71 is then permitted to move angularly about its pivot 72 so that the 5 jaws are actuated to crimp the strap and shear its edges as hereinafter described, it being understood that after the strap has been cut off from the source of supply a portion of the upper end of the strap will overlie the extremity of the 10 lower portion 12^a so that when the head 59 is moved downwardly, these overlapping portions are forced together and are then operated upon to deform them into interlocking relation. Owing to the frictional engagement of the plate 15 60 with the bearing hubs 54 and 53, the head 59 is adapted to maintain any position in which it may be put unless it is positively moved therefrom.

Referring now to the means for crimping and 20 shearing the edges of the overlapping portions of the strap to form an interlocking joint, it will be seen upon referring to Figs. 16, 17 and 18 that each jaw comprises a pair of side plates 85, a center plate 86, and two intermediate 25 plates 87, each of the latter plates being interposed between the center plate and one of the side plates. These plates are secured together by rivets 88 and the intermediate plates have parts 87^b extended inwardly and milled off on 30 one side to interfit with the corresponding parts of the opposite plates and to receive the pin 67 about which the jaws have pivotal movement. The intermediate plates 87 have other parts 87^a thereof extended upwardly to form the arms 66^a 35 of the jaws which are connected to the links 69. The lower strap engaging portions of the jaws beneath the pivotal axis 67, are provided with parts adapted to receive and operate upon the overlapping ends of the strap 12. For this purpose, 40 the edges of the plates 85 of each jaw are provided with notches 85^a of rectangular cross section extending inwardly from the upright face of the jaw and similar notches 86^a of rectangular cross section extend inwardly from the edges 45 of the center plate 86. The notch in each center plate registers with the notches 85^a in the plate 85 of the same jaw and the notches in the plates of one jaw are disposed oppositely to the notches in the plates of the other jaw so that they 50 register with each other when the jaws are closed upon each other as shown in Fig. 16. The intermediate plates 87 are provided with notches 87^c which are of curved cross section and which register partially with the notches 85^a and 86^a of the respective jaws. The notches 87^c, however, 55 are of larger vertical dimensions and project below the openings of the notches 85^a and 86^a, as shown in Fig. 18. The side plates 60 of the head 59 are cut away as shown at 60^a so that when 60 the head 59 is lowered the openings 60^a are adapted to receive the overlapping ends of the strap and to hold these overlapping ends in a position wherein they may be engaged by the notches of the jaws when these jaws are closed upon them by the movement of the lever 71. A 65 flange 90 projects forwardly from the base 15 to support the extreme end of the portion 12^a of the strap and the side plates 60 of the head are adapted to engage the upper portion of the strap and to bring the two parts of the strap 70 into close overlapping relation with each other with parts of the strap on opposite sides of the head supported from below by the flanges 16 and 90. The base 15 is further provided with a curved 75 recess 91 extending inwardly from the space be-

tween the flanges 16 and 90 to accommodate the lower portions of the jaws 66, as shown particularly in Fig. 16. The vertical dimensions of the recesses 85^a and 86^a are such that they are closely fitted by the overlapping strap ends and the depth of the recesses is such that they are completely occupied by the strap ends when the two jaws are closed upon each other, as shown in Fig. 16. The flat surfaces of the walls of these notches hold the strap ends in a flat 10 condition while the portions of the strap between the plates 85 and the center plate 86 are curled or beaded due to the action of the curved notches 87^c which are formed in the plates 87. The side plates 85 and the center 15 plate 86 serve to hold the strap in such a position that the plates 87 will always curl or crimp the edges of the strap in the same direction. The notches 85^a and 86^a also serve to center the strap ends so that they receive the same amount of 20 curling or beading along each edge thereof. The plates 85 and 86 also act as shearing dies to cooperate with the plates 87 in shearing the overlapping portions of the strap at the ends of the curled or beaded portions.

The action of these jaws 66 upon the overlapping ends of the strap is illustrated particularly in Figs. 2 to 6, inclusive, where the joint formed by the device is illustrated. As shown in these figures, the joint 95 comprises the two overlapping strap ends 12^a and 12^b which are deformed so that there is an intermediate flat portion 95^a, two end portions 95^b and two intermediate pairs of rolls or beads 95^c which form indentations in the sides of the strap represented at 95^d in Fig. 2. The beads or rolls 95^c may be of more or less complete circular cross section depending upon the formation of the recesses or notches 87^c in the plates 87 and they have a telescoping engagement with each other so that they effectively prevent separation of the overlapping strap ends in any direction transverse to the length of the strap. These beads or rolls also have a longitudinal curvature, diverging away from each other on opposite sides of the strap ends so that they prevent relative longitudinal movement of the strap ends, but this relative longitudinal movement is further prevented by the shearing of the edges of the strap ends to form inwardly extending cuts 95^e at each end of each of the beads. These cuts are formed by the cutting edges 87^b of the plates 87 which act as cutting dies so that when they engage the edges of the strap the edges of the strap are sheared at the same time that the portions of the strap between the cuts or shears are turned inwardly to form the beads 95^c. These cuts 95^e provide shoulders which contact with the transversely extending shoulders on the ends of the beads to prevent any possible relative endwise movement of the two overlapping strap ends. As a result of the curling and shearing of the strap ends they are bowed upwardly to a slight extent in the region of the joint, as shown in Fig. 4. In this way an effective joint is obtained without the use of any enclosing sleeve or seal such as has heretofore been employed with many forms of sealing devices. The form of seal or joint hereinabove described is claimed in my co-pending application Serial No. 592,051, filed February 10, 1932.

In the operation of the device, the base plate 15 is seated upon the surface of the box or package about which the strap 12 is to be secured, as shown in Fig. 1. The free end of the strap is then placed beneath the gripping dog 18 on the 75

flange 16 with the extremity thereof extending over the opening between the flange 16 and the flange 90. Then, after passing the strap around the box or package, the supply portion 12^b there-
 5 of is inserted beneath the gripping dog 26 and the flange 27^a of the movable block 27, from which point the supply portion of the strap ex-
 tends above the free end of the strap and through the slot 18^b of the gripping dog 18 where it is held
 10 in place by the spring-pressed ball 25. The parts are then in readiness for drawing the strap taut, which is effected by moving the lever 50 in a rear-
 ward direction, as shown in Fig. 14, thereby caus-
 15 ing a forward movement of the hollow link 45
 with a resulting forward motion of the rear end of the lever 41 to which motion is imparted
 through the spring 46. As the lever 41 moves forwardly, its forward end swings toward the left, as viewed in Fig. 7, thereby actuating the
 20 sliding bar 28 upon which the block 27 is mount-
 ed. The movement of the block 27 carries with it the gripping dog 26 and flange 27^a between which the supply portion of the strap is gripped so that the strap is thereby drawn taut around
 25 the package. When a predetermined degree of tautness is attained, the coil spring 46 within the hollow link is further compressed so that further movement of the lever 50 and hollow link 45 will not effect any further tightening of the strap.
 30 The movable head 50 is then swung downwardly toward the right, as viewed in Fig. 14, while retaining the lever 71 in its upright position. The initial motion of the head 50 is adapted to cut off the strap from the source of supply due to
 35 the actuation of the cutting lever 75 which en-
 gages the supply portion of the strap seated on the flange 79. The cut-off end of the strap is then pressed downwardly against the free end which rests upon the flanges 16 and 90 and these
 40 overlapping ends then enter the notches 60^a in the side plates 60 of the head, as the downward motion of the head is continued. The lever 71 is then swung forwardly about its pivot 72 with the result that the jaws 66 are actuated to form
 45 telescoping beads along the edges of the overlap-
 ping portions of the strap at points which are spaced apart, as shown in Fig. 4, while at the same time shearing the lateral edges of the strap ends, as shown at 95°, to insure further the se-
 50 curity of the interlocking joint.

Although one form of the invention has been shown and described by way of illustration, it will be understood that it may be constructed in various other embodiments within the scope of
 55 the appended claims.

I claim:

1. The combination in a strap stretching de-
 vice, of a pair of blocks having relative linear
 60 movement, gripping means carried by said blocks
 for gripping the opposite ends of a strap, and
 operating means for moving said blocks toward
 each other to draw said strap taut around a
 package, said operating means comprising rela-
 65 tively movable parts adapted to yield after a
 predetermined tension has been set up in said
 strap.

2. The combination in a strap stretching de-
 vice, of a base plate, a pair of blocks carried by
 70 said base plate, one of said blocks being mounted
 for sliding movement with respect to the other
 block, gripping means carried by said blocks for
 gripping the opposite ends of a strap, means move-
 able transversely to said strap for actuating said
 75 movable block to draw said strap taut around a
 package, said last named means including rela-

tively movable parts adapted to yield after a predetermined tension has been set up in said strap.

3. The combination in a strap stretching de-
 vice, of a base plate, a stationary gripping device
 5 and a relatively movable gripping device carried
 by said base plate for gripping opposite end por-
 tions of a strap passed around a package, one of
 said gripping devices being mounted for sliding
 movement on said base plate, and operating
 mechanism carried by said base plate for effect-
 ing relative movement of said gripping devices,
 said operating mechanism comprising a yieldable
 connection to permit extension of said mechanism
 10 after a predetermined tension has been created
 in said strap.

4. The combination in a strap stretching de-
 vice, of a base plate, a pair of gripping devices
 carried by said base plate for gripping opposite
 20 end portions of a strap, a bar upon which one of
 said gripping devices is mounted, said bar being
 slidably mounted upon said base plate, a link
 pivoted on said bar, a lever having an interme-
 diate part pivoted on said link and having one
 25 end pivoted on said bar, and operating mecha-
 nism connected to the other end of said lever for
 effecting movement of said bar.

5. The combination in a strap stretching de-
 vice, of a base plate, a pair of gripping devices
 carried by said base plate for gripping opposite
 30 end portions of a strap, a bar upon which one of
 said gripping devices is mounted, said bar being
 slidably mounted upon said base, a link pivoted
 on said bar, a lever having an intermediate part
 pivoted on said link and having one end pivoted
 35 on said bar, and operating mechanism connected
 to the other end of said lever for effecting move-
 ment of said bar, said mechanism including a
 resilient connection adapted to yield when a pre-
 determined tension is obtained in the strap.
 40

6. The combination in a strap stretching de-
 vice, of a base, a pair of gripping devices carried
 by said base, a bar slidably mounted on said base
 and having one of said gripping devices mounted
 thereon, lever mechanism for effecting movement
 45 of said bar, and means for operating said lever
 mechanism including a spring for permitting ex-
 tension of said mechanism after a predetermined
 tension has been created in the strap.

7. The combination in a strap stretching de-
 vice, of a base, a pair of gripping devices carried
 by said base, a bar slidably mounted on said base
 and having one of said gripping devices mounted
 thereon, lever mechanism for effecting movement
 55 of said bar, a hollow link connected to said lever
 mechanism, means for effecting movement of
 said hollow link, and a spring mounted in said
 hollow link and adapted to be compressed when
 said lever mechanism is actuated.

8. The combination in a strap stretching de-
 vice, of a base, a pair of gripping devices carried
 by said base, a bar slidably mounted on said base
 and having one of said gripping devices mounted
 thereon, a lever pivoted on said base and movable
 60 transversely to the direction of movement of said
 bar, operating mechanism connected between
 said lever and said bar for effecting movement of
 said bar to draw taut a strap passed around a
 package and held by said gripping devices, and
 means for causing said operating mechanism to
 65 set up a predetermined tension in said strap.

9. The combination in a strap stretching de-
 vice, of a base, a pair of gripping devices carried
 by said base, a bar slidably mounted on said base
 and having one of said gripping devices mounted
 75

- thereon, a lever pivoted on said base and movable transversely to the direction of movement of said bar, operating mechanism connected between said lever and said bar for effecting movement of said bar to draw taut a strap passed around a package and held by said gripping devices parallel to the path of movement of said bar, and additional means carried by said base plate for cutting off said strap when it has been drawn taut.
10. The combination in a strap stretching device, of a base, a pair of gripping devices carried by said base, a bar slidably mounted on said base and having one of said gripping devices mounted thereon, a lever pivoted on said base and movable transversely to the direction of movement of said bar, operating mechanism connected between said lever and said bar for effecting movement of said bar to draw taut a strap passed
- 15

around a package and held by said gripping devices parallel to the path of movement of said bar, and a cutting blade pivoted on said base plate and movable transversely to said strap for cutting said strap off from the source of supply 5 when it has been drawn taut.

11. The combination in a strap stretching device, of a pair of relatively movable gripping devices adapted to grip opposite end portions of a strap looped around an object to be strapped, 10 and operating mechanism for effecting a relatively rapid relative movement of said gripping devices in the early stages of the stretching operation and for producing a decreasing rate of relative movement of said devices as the strap approaches its taut condition. 15

WILLIAM C. CHILDRESS.
